HIS ATTORNEYS.

UNITED STATES PATENT OFFICE.

GEORGE BULLOCK, OF GRAND JUNCTION, COLORADO.

ROLL-PAPER CONTROLLER.

Application filed October 3, 1921. Serial No. 504,962.

To all whom it may concern:

Be it known that I, GEORGE BULLOCK, a citizen of the United States, residing at Grand Junction, Mesa County, Colorado, 5 have invented a new and useful Roll-Paper Controller, of which the following is a specification.

This invention relates to a roll paper controller.

10 It is now the usual practice to support a roll of wrapping paper in a frame provided with a blade that is pressed against the paper roll by an actuating device, such as a spring or a weight. The paper is torn off 15 along the edge of the blade so that when it is again desired to take paper from the roll it is necessary to turn the roll a distance by hand before the edge of the paper can be engaged. This present construction also admits of the paper being taken from only one 20 side of the roll.

The blade against which the paper is torn serves well enough to clamp the paper to 25 permit it to be torn off when the roll is full or large; but as the paper is taken from the roll and the size of the roll diminishes the clamping effect of the blade against the roll is lessened, often with the result that the 30 paper will be torn unevenly since the pressure of the blade is not sufficient to hold the paper firmly while the paper is being torn.

An object of the present invention is to provide an improved roll paper controller in which after each piece of paper is torn off, a sufficient portion of the paper is left 35 for easy manual engagement when it is again desired to take paper from the roll.

Another object of the invention is to provide an improved roll paper controller in 40 which the paper can be taken toward either side with equal facility and in which a sufficient portion of the paper is left projecting free from the clamping device for manual engagement.

45 Another object of the invention is to provide an improved roll paper controller in which the paper will be firmly clamped and held when a piece of paper is being torn off for use, irrespective of the size of the roll or the amount of paper on the roll.

Another object of the invention is to pro-

vide an improved roll paper controller overcoming all of the objections above mentioned.

Other objects of the invention will appear from the following description, reference being made to the drawing, in which—

Fig. 1 is a side elevation of a roll paper controller embodying my present invention.

Fig. 2 is a vertical sectional view on the line 2—2 of Fig. 1.

In the embodiment of the invention shown the two upright standards 1 are secured in proper position relative to each other and may have their upper ends connected by the cross or tie member 2. A roll 3 of paper is supported between the uprights 1 upon an axial support 4. The ends of the axial support 4 extend into vertical slots 5 in the uprights 1 permitting downward movement of the paper roll as the paper is taken off and as the size or diameter of the roll diminishes.

A smaller roll 6 has axial extensions 7 on its opposite ends extending into short slots 8 in the uprights 1. The slots 8 are at one side of the vertical plane of the axis of the support 4 so that the pressure of the paper roll 3 upon the roller 6 actuates said roller outwardly until the axial members 7 are at the outer ends of the slots 8. This is because the weight of the paper roll 3 imparts a lateral pressure upon the roll 6, due to the position of said roller at one side of the vertical plane of the axis of the paper roll.

A pivoted clamp and tear device is supported at one side of the roller 6. As shown, said device comprises a plate 9 having ears 10 extending from the opposite ends thereof and pivoted upon supports 11 in connection with the uprights 1. The inner edge of the plate 9 is provided with an up-turned flange 12 located adjacent to and curving in substantial conformity with the curvature of the surface of the roller 6. The paper from the paper roll 3 is passed downwardly between the roller 6 and the flange 12. The end of the paper hangs down a sufficient distance for convenient manual engagement from either side of the paper roll so that the paper may be drawn in either direction.

100 The outer edge of the plate 9 is formed with a downwardly turned flange 13. When the

paper is drawn out a sufficient distance for the piece of paper desired it is raised against and torn along the flange 13. As the paper is raised and torn the outer edge of the plate 5 9 is raised and the flange 12 is pressed or clamped against the paper between said flange and the roller 6. By this clamping action the paper is held from further movement so that the paper will be torn straight 10 across along the edge of the flange 13.

After the piece of paper has been torn off the free edge of the paper drops down so that it can be conveniently engaged from either side of the paper roll. The outer portion 15 of the plate 9 is normally sustained by supporting lugs or projections 14 in connection with the uprights 1. The lugs 14 do not interfere with the clamping action of the device.

20 A plate 15, having ears 16 pivoted upon supports 17 in connection with the uprights 1, is supported at the opposite side of the roller 6 from the plate 9. The width of the plate 15 added to the diameter of the roller 25 6 is the same, or approximately the same, as the width of the plate 9 so that about the same length of paper will be left extending below the roller 6 for manual engagement, irrespective of the side at which the 30 paper is torn off. The outer edge of the plate 15 has a down-turned flange 18 along which the paper will be torn when taken from that side of the device. The inner edge of the plate 15 has an up-turned flange 35 19 curving approximately to the curvature of the surface of the roller 6 and arranged to press against the roller 6 when the outer portion of the plate 15 is raised by tearing the paper along the flange 18. The pressure 40 of the flange 19 against the roller 6 forces the roller 6 over against the flange 12, causing the paper to be clamped between the roller and said flange. This holds the paper so that the paper will be torn straight 45 across along a line defined by the edge of the flange 18. Normally the outer portion of the plate 15 is supported by lugs or projections 20 in connection with the uprights 1.

50 The lower edges of the flanges 13 and 18 may be formed with teeth or not, as desired. If the flanges are formed with teeth for puncturing the paper, the paper may be separated more easily and with less pressure 55 than otherwise.

From the foregoing it is apparent that my invention obtains all of its intended objects in a highly convenient, efficient and simple manner. There is always sufficient 60 paper left for easy manual engagement, irrespective of the side from which the paper is taken and the paper may be taken from either side of the paper roll with equal facility.

65 The clamping device is effective to hold

the paper so that the same will be torn along a straight line defined by the cutting or tearing flange.

I do not restrict myself to unessential features, nor to the exact construction and arrangement shown. It is apparent that the construction and arrangement of the parts may be varied without departure from the nature and principle of the invention, and I contemplate such variations as may be 75 desired and as are within the scope of the appended claims.

What I claim and desire to secure by Letters Patent is:—

1. In a device of the character described, 80 the combination of a pair of standards, a support for a paper roll mounted in the standards for vertical movements, a rotative roller supported by the standards for supporting the paper roll, an element against 85 which the paper is drawn in order to separate a piece of paper from the paper passing from the roll, and means controlled by said element to clamp against said roller the paper from which the piece of paper is separated.

2. In a device of the character described, 90 the combination of a support for a paper roll, a rotative roller for supporting the paper roll, a clamp device arranged to clamp the paper against said roller and prevent the roll from being turned when a piece of paper is separated from the paper passing from the roll, and an element against which the paper is drawn in order to separate or 95 detach a piece of paper from the paper passing from the roll and to leave a loose end of the paper extending downwardly between said clamping device and said roller.

3. In a device of the character described, 100 the combination of a support for a paper roll, a rotative roller for supporting the paper roll, an element against which the paper is drawn to separate a piece of paper from the paper passing from the roll, and a 105 clamping device between said element and the point at which the paper leaves the roll for clamping the paper against said roller and preventing further movement of the paper during the separation of a piece of 110 paper, said element being spaced a sufficient distance from said clamping device and said roller to leave a free end of the paper extending downwardly below said parts after the piece of paper has been separated.

4. In a device of the character described, 115 the combination of a support for a paper roll, a rotative roller for supporting the paper roll, an element against which the paper is drawn to separate a piece of paper 120 from the paper passing from the roll, a pivoted support for said element, and a clamping device between said element and a point at which the paper leaves the roll in position to cooperate with said roller to guide 125

the paper drawn from the roll and controlled by said element and said pivoted support to clamp the paper against said roller as an incident to the use of said element to 5 separate a piece of paper.

5. In a device of the character described, the combination of a support for a paper roll, a pair of guide members for the paper passing from the roll having one member thereof arranged to support the paper roll, and an element against which the paper is drawn to separate a piece of paper from the paper passing said guide members, said element being spaced from said guide members to leave a part of the paper extending beyond the guide members after the piece of paper has been separated.

6. In a device of the character described, the combination of a support for a paper roll, a pair of guide members for the paper passing from the roll having one member thereof arranged to support the paper roll, an element against which the paper is drawn to separate a piece of paper from the paper passing said guide members, said element being spaced from said guide members to leave a part of the paper extending beyond the guide members after the piece of paper has been separated, and means whereby said

30 element will operate one of said guide mem-

bers to clamp the paper against the other and prevent the roll from being turned as an incident to the use of said element.

7. A device of the character described, comprising a support for a paper roll, a 35 guide for the paper passing from the roll, and for supporting the paper roll, a device at each side of said guide against which the paper is drawn to separate a piece of paper from the paper passing through said guide, 40 and means operated by each of said guides for clamping the paper in the guide as an incident to the separation of a piece of paper as aforesaid.

8. In a device of the character described, 45 the combination of a frame having a vertical slot in each side thereof, a paper roll support movable vertically in said slots, a roller for supporting the paper roll, a device for holding the paper passing from the roll close to 50 said roller, a pivoted member supporting said device, and an element on said pivoted member against which the paper is drawn to separate a piece of paper from the paper that has passed between said device and the 55 roller and arranged to operate said device to clamp the paper against the roller to prevent the roller from being turned.

GEORGE BULLOCK.
